(57) **CLAIM**

The ornamental design for a rechargeable battery, as shown and described.

DESCRIPTION

FIG. 1 is a front, top, right perspective view of a rechargeable battery showing our new design;

FIG. 2 is a front, bottom, left perspective view thereof;

FIG. 3 is a front elevational view thereof;

FIG. 4 is a right side elevational view thereof;

FIG. 5 is a top plan view thereof; and,

FIG. 6 is a bottom plan view thereof.

Portions in broken lines are for illustrative purpose only and form no part of the claimed design. The dot-dash broken lines define but are not included in, the boundaries of the claimed design.
